Primary Examiner — John R Yeh(74) *Attorney, Agent, or Firm* — CANTOR COLBURN LLP(57) **CLAIM**

The ornamental design for a spin mop brush for cleaner, as shown and described.

DESCRIPTION

FIG. 1 is a front perspective view of a spin mop brush for cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the delineated portion 8 in FIG. 1.

The dot-dash broken lines in FIG. 1 indicate the locations from which a corresponding enlarged view is taken. The dot-dash broken lines in FIG. 8 encircling the detailed view represent the bound of the view.

The dot-dash broken lines form no part of the claimed design. The remaining broken lines illustrating portions of the spin mop brush for cleaner form no part of the claimed design.
